UNITED STATES PATENT OFFICE.

HENRY GREEN, OF FORT WORTH, TEXAS.

SELF-PRIMER VACUUM-FEED CARBURETOR.

Application filed September 25, 1920. Serial No. 412,630.

This invention relates to new and useful improvements in carburetors and has for its primary object to provide a priming and idling device associated with the carburetor proper so that gasoline and air will be drawn into the intake pipe when the engine starts and as soon as the supply of gasoline in the priming and idling device is just about exhausted or used by the engine starting, a mixture of gasoline and air will be drawn into the intake pipe to cause the engine to run at an idling speed.

Another important object of the invention resides in the combination of a carburetor and vacuum device with an intake pipe having a throttle valve therein, said carburetor including a primer and idling device the latter of which has communication with the intake pipe between the throttle valve and the engine.

Another object of the invention resides in the provision of the combination of an intake pipe, a carburetor and a vacuum supply chamber the latter having communication with the intake pipe between the throttle valve therein and the engine whereby a vacuum may be created in the vacuum chamber regardless of the position of the throttle valve.

A still further object of the invention resides in the provision of a carburetor having a vacuum supply device associated therewith in such a manner that a vacuum will be automatically created in the supply device when the supply of fuel in the carburetor and the supply device proper has been exhausted or just about exhausted, thereby providing a carburetor which will be properly supplied with fuel regardless of the position of the main fuel tank.

Another object of the invention resides in the provision of a carburetor built in a number of sections whereby the carburetor can be readily assembled and disassembled.

Other objects and advantages of the invention will become apparent during the course of the following description.

In the accompanying drawings forming a part of the application and wherein like numerals are employed to designate like parts throughout several views.

Figure 1 is a vertical section through the carburetor embodying my invention, and

Figure 2 is a transverse section taken on the line 2-2 of Figure 1.

Referring now to the drawing wherein for the purpose of illustration is shown the pre-

ferred embodiment of my invention, the carburetor is shown in the vertical section in Figure 1 and consists of a plurality of detachable parts one of which is an intake pipe 7 having one end flanged as at 8, whereby the same may be connected to an internal combustion engine. This intake pipe 7 is provided with a longitudinally extending opening 9 extending from the end 60 of the intake pipe which is flanged and terminating in a curved passage which communicates with the carburetor in a manner which will be fully described hereinafter. A throttle valve 11 of the well known construction 70 is mounted in the opening 9 of the intake pipe 7. The end of the intake pipe 7 opposite the flanged end is provided with a fuel inlet passage 12 having an inner vertical extension 13. It is of course understood that the inlet passage 12 is connected by means of a conduit 75 14 to a fuel supply tank, not shown.

The angular extension 13 of the fuel inlet passage 12 opens into the top surface of the intake pipe 7 to communicate with a vertically extending inlet passage 15 of a vacuum chamber designated in its entirety by the numeral 16 and secured by means of fastenings 17 to the top surface of the intake pipe 7. The passage 15 extends upwardly to a point 80 adjacent the top of the vacuum chamber 16 and opens therewith, the admission of fuel into the chamber 16 through the passage 15 being controlled by an inwardly opening needle valve 18, slidably mounted in a bracket 90 19 carried by a horizontal spider 20 arranged within the chamber 16, and controlled by a mechanism which will be presently described.

The opposite wall of the reservoir 16 is provided with a vertically extending suction 95 passage way 21 which communicates with the upper end of the fuel reservoir 16, this end of the passage way being also controlled by an inwardly opening needle valve 22 slidably mounted within the reservoir 16 in a bracket 23 rising from the spider 20. This needle valve is also actuated by the float controlled mechanism which operates the needle valve 18. The lower end of the suction passage way 21 communicates with one end of a longitudinally extending suction conduit 24 provided in the intake pipe 7 and the opposite end of this conduit communicates with the opening 25 in the intake pipe 7 beyond the throttle valve 11.

The upper end of the fuel reservoir 16 is provided with a vent opening 26 which is

controlled by an inwardly opening sliding needle valve 27 mounted in the bracket 23 of the spider 20. In order to intermittently operate the plurality of valves in the reservoir 16, a float 28 is arranged within the reservoir 16 and equipped with a vertically extending stem 29 slidably mounted through the spider 20 and extending thereabove. This stem 29 is provided with two pairs of spaced collars 10 or abutments, the uppermost being designated by the numeral 30, while the lower are indicated by the numeral 31. Angle levers 32 are pivoted between their ends upon opposite sides of the float stem 29 so that their inner 15 ends may be arranged between the two lowermost collars 31. The outermost ends of these levers are extended at right angles and equipped with vertically extending slots 33 in which pins 34 of the needle valves 18 and 22 are adapted to operate. The inner end of an angle lever 35 is disposed between the uppermost collars 30 of the float stem 29, and the lever is pivoted between its ends to an upstanding post of the spider to which one of 20 the angle levers 32 is pivoted. The outer end of the lever 35 is extended downwardly at right angles and equipped with a slot to receive a pin carried by the needle valve 27 which controls the vent opening 26.

30 It will therefore be seen that when the level of the fuel within the reservoir 16 is below its predetermined level, the float 28 will have moved downwardly within the reservoir 16 to cause the outer ends of the angle levers 32 to 35 move inwardly and consequently open the needle valves 18 and 22, while the angle lever 35 will be moved to close the valve 27. Consequently, on the suction stroke of the engine to which the carburetor is attached, suction will 40 be created within the reservoir 16 and through the suction passage way 21 of the fuel reservoir 16 and intake pipe 7 respectively, thereby causing additional fuel to be drawn from the supply tank and entered into the reservoir 45 16. During the downward movement of the float 28, an abutment or collar 36 carried by the float stem 29 engages the inner ends of a pair of counter-weight levers 37 which are pivoted between their ends to depending supports carried by the spider 20. The outer 50 end of each lever 37 is equipped with a counter-balance weight so that they will retard the downward movement of the float 28 and assist its return. When the float 28 again 55 rises to its predetermined point, the valves 18 and 22 are automatically closed, while the needle valve 27 is opened whereby the fuel from the reservoir 16 will pass downwardly through a conduit 38 in the intake pipe 7 and 60 conduit 39 in an air inlet casting 40 which will be presently described.

The air inlet casting 40 has its inner end enlarged into a ring like head, the central opening 41 therein having communication 65 with an elongated passage 42 through which

air is admitted into the carburetor. An ordinary butterfly valve 43 is positioned in the passage 42 to regulate the amount of air passing therethrough into the carburetor. The top edge of the opening 41 is provided with an 70 annular recess 44 in which is seated an out turned flange 45 of a downwardly tapered tubular deflector member 46 constituting a mixing chamber. The air inlet casting 40 is secured by suitable fastenings to the underside of the intake pipe 7 so that the inner edge 10 of the opening through the intake pipe 7 opens into the upper end of the deflector 46, and the flange 45 of the deflector is clamped as clearly shown between these two 80 castings.

Secured to the lower edges of the opening 41 is a downwardly tapered enclosing shell 47 which is adapted to surround the deflector 46 in spaced relation whereby air may enter 85 the opening 42 of the casting 40 and pass downwardly between the deflector 46 and the shell 47. The bottom of the enclosing member 47 is spaced from the lower edge of the deflector 46, and is provided with an upstanding nozzle 48 having a conical upper end whereby a needle valve 49 may operate therein for adjusting the amount of fuel entering the mixing chamber. The bottom of the shell 47 is provided with a depending chamber 50 95 having its bottom equipped with a tabular exteriorly threaded depending extension 51 which is adapted to extend through an opening in the bottom of the carburetor bowl 52 for threaded engagement with a packing nut 100 53 surrounding the lower end of the needle valve 49. The shell 47 is fastened to the bottom of the intake pipe casting 40 in any suitable manner, and the threaded cap 53 and the similar cap associated with the screw valve 67 105 both assist in supporting the float bowl 52 and clamping the same against the intake casting 40.

Opposite sides of the chamber 50 are apertured and to one of the sides is secured a laterally extending cell 54 having its outer end equipped with a port which is controlled by an inwardly extending valve 55 mounted in the cell. This valve 55 is normally disposed in an open position so that fuel from the bowl 115 52 can enter the chamber 50. However, should the supply of fuel ever become exhausted from the bowl 52 suction in the bowl 52 and the vacuum reservoir 16 acting through the passage 21 will cause the valve 55 to close whereby the proper vacuum within the vacuum reservoir 16 can be created in order to draw a fresh supply of fuel from the main fuel tank into the vacuum reservoir 16.

To the opposite apertured side of the chamber 50 is secured one end of a pipe 56 extending toward the side of the bowl 52, this pipe is provided with a pair of upstanding conduits 57 and 58, the former being a fuel 130

conduit, while the latter is designed as an air intake conduit. A primer reservoir or shell 59 surrounds the tube 57 in spaced relation thereto and the top of the reservoir 59 is provided with an upstanding extension 60 which communicates with one end of a vertical port 61 in the air intake casting 40. This port in turn communicates with a longitudinally extending conduit 62 in the intake pipe 7, the other end of this conduit opening at two points 63 in the opening 9 of the intake pipe 7 beyond the throttle valve 11. A valve adjusting screw 64 is associated with the intake pipe 7 to control the conduit 62.

15 The upper end of the air inlet tube 58 communicates with a port or vent opening 65 in the air inlet casting 40, while the lower end of the tube besides communicating with the pipe 56 communicates with the lower end 20 of the primer reservoir 59 as at 66. In order to control the admission of fuel into the primer reservoir 59, a valve in the form of an adjusting screw 67 is threaded through a depending extension 68 of the pipe 56 to 25 be in vertical alignment with the tube 57. The depending extension 68 is, as seen, clamped to the bottom of the bowl 52 whereby the pipe 56 and the associated parts are properly supported.

30 The float in the bowl 52 is provided with an upstanding needle valve 70 which is adapted to control the passage of fuel through the port 39. The needle valve 70 is mounted on a movement controlling means which in the 35 present instance is in the form of a rod 69 pivotally mounted between its ends to a depending support 72 carried by the air intake casting 40 and said rod 69 having a free hooked end 73 which is adapted for engagement with the support 72 when the float lowers to a certain extent so as to limit the movement of the float and to prevent the needle valve 70 becoming disengaged from the outer end of the port 39.

45 By referring to Figure 1 of the drawings, it will be seen that the bowl 52 is secured by its upper edges to the bottom of the intake casting 40 and inasmuch as the enclosing member 47 is secured to the bottom of the 50 air intake casting 40, it projects into the bowl 52 below the predetermined level of the fuel therein. Obviously then, the air intake casting 40 and the bowl 52 constitute the carburetor proper.

55 It is to be recalled that the ports 25 and 63 open into the intake passage 9 between the throttle valve 11 and the engine with which the device is associated. Consequently, when the engine is running, a continuous suction 60 through the passage 21 is created regardless of the position of the throttle valve 11. When the level of the fuel in the vacuum chamber 16 recedes and permits the float 28 to lower, it will be understood from the 65 construction and arrangement of the valves in

the vacuum tank 16 hereinbefore set forth, that the valve 27 will close the air port 26 and simultaneously therewith, the valves 18 and 22 will be caused to open, thereby permitting the suction acting through the passage 21 to exhaust all air in the vacuum chamber and cause a suction through the fuel inlet passage 15 whereby an additional supply of fuel will be drawn into the vacuum chamber 16 from the main supply tank. As 70 soon as the maximum amount of fuel has been caused to flow into the vacuum chamber 16 the float 28 will have been elevated so as to open the air port 26 and close the passages 75 15 and 21.

It will also be recalled that the passage 62 opens into the intake passage 9 at two spaced points 63 which are disposed between the throttle valve and the engine, and by reciting simply an opening or openings 63, I will state 80 that their action is the same as that of a single such opening. While the fuel is passing into bowl 52 it will rise to its maximum height, and if valve 67 is open, it will be appreciated that fuel from the bowl 52 will 85 pass through the tube 56 and up into the tube 57 to overflow and empty into the primer chamber 59 until the level of fuel therein rises to the same height as the level of the fuel in the carburetor bowl 52. When the 90 engine is started, the throttle valve 11 will be closed so that suction through the intake pipe will create a suction in the passage 62 and draw the fuel mixture in the primary chamber 59 into the intake pipe and thence 95 into the cylinders of the engine where it will be readily exploded. With such a rich mixture of fuel passing to the cylinders of the engine, it will be appreciated that the engine will readily start running and will 100 draw all of the fuel in the primer chamber 59 therefrom until it has just about exhausted the same. When this happens, the port 105 66 communicating the primer reservoir 59 with the air tube will be opened and air will 110 be drawn into the primer chamber 59 and subsequently into the passage 62 through the ports 63. At the same time, fuel will be drawn up by the suction in the passage 62 through the tube 57 so that a combination 115 of air and gasoline will be sucked into the intake passage 9 to cause the engine to run at an idling speed.

Thus, when the throttle valve 11 is opened to start the vehicle moving, then the carburetor proper will come into play and permit a combustible charge to be drawn up through the deflector 46 in the customary manner to furnish the engine with the ordinary combustible charge. It is to be borne in mind that the opening and closing of the throttle valve 11 in no way effects the continuous suction which is created in the passage 24, and that the minute the level of fuel 125 in the vacuum chamber recedes, the valve 27 130

will be promptly closed to permit the suction in passage 24 to draw in an additional quantity of fuel into the vacuum chamber 16 as hereinbefore described.

5 It will of course be obvious that the level of fuel in the carburetor bowl 52 is maintained at a predetermined level by the float operating the valve 70 which controls the passage of fuel from the vacuum chamber 16 10 down into the carburetor bowl 52. Consequently, it will be appreciated that a carbureting and priming device has been provided which will at all times be well supplied with fuel regardless of the position of the 15 fuel tank on the motor vehicle or the inclination at which the vehicle is disposed with respect to the horizontal.

The foregoing description and the accompanying drawings have reference to the preferred or approved embodiment of my invention. It is to be understood however, that such changes may be made in construction and arrangement of parts, materials, dimensions, etc. as may prove expedient and fall 25 within the scope of the appended claims.

Having thus described my invention what I claim as new is:

1. The combination with an intake pipe for internal combustion engines having a throttle 30 valve therein, a conduit communicating with the intake pipe to one side of the throttle valve, a carburetor having a bowl associated with the intake pipe at the opposite side of the throttle valve, an atomizing device associated with the carburetor and including a 35 valved chamber having depending threaded extension, a needle valve extended through said extension, a primer reservoir situated within the carburetor bowl and having communication at its upper end to said conduit, a pipe communicating with the valved chamber of the atomizer and having an end extended up into the primer reservoir to a point adjacent its upper end, said pipe being provided with a depending threaded nipple, a 40 needle valve extended through said last mentioned nipple to control the flow of fuel through the upstanding portion of said pipe, the carburetor bowl being provided with 45 apertures to receive the threaded nipples of the pipe and valved chamber, and caps threaded on said nipples to provide boxes for the needle valves and for supporting the carburetor bowl.

55 2. In combination, an intake pipe, a carburetor secured thereto and comprising a pair of sections, one of said sections having an opening therein, a deflector arranged within the opening and having its upper end clamped 60 between one of said sections and intake pipe, a shell depending from one of said sections and adapted to surround the deflector, a chamber depending from said shell and having a threaded nipple, a carburetor bowl surrounding the shell and having an aperture 65

to receive the threaded nipple, a needle valve extending through said nipple, and a cap threaded on the nipple to assist in supporting the bowl.

3. The combination with an intake pipe 70 and carburetor associated therewith, of a vacuum chamber associated with the carburetor for supplying the carburetor with fuel, a supply device for the vacuum chamber, a conduit communicating with the upper end 75 of the vacuum chamber and with the intake pipe, float controlled valves in the vacuum chamber, said chamber having communication with the carburetor, an atomizer in the carburetor, a valve for controlling the flow 80 of fuel to the atomizer, and a valve adapted to automatically close when the supply of fuel in the carburetor and vacuum chamber have been exhausted whereby a vacuum will be created in the vacuum chamber by the 85 suction in the intake pipe whereby a supply of fuel will be drawn into the vacuum chamber from the main supply tank.

4. The combination with an intake pipe and carburetor associated therewith: of a 90 vacuum chamber associated with the carburetor for supplying the same with fuel, a conduit leading from the vacuum chamber to the carburetor chamber, a float controlled valve associated with said conduit, a chamber 95 arranged within the carburetor chamber and forming a part of an atomizer, said atomizer chamber having an opening therein to admit fuel from the carburetor chamber, a valve associated with said opening, said vacuum chamber having a gasoline inlet port, and a suction port having communication with the intake pipe beyond the throttle valve, said vacuum chamber also being provided with an air port, a valve for each of the ports in the 100 vacuum chamber, and float controlled means in said vacuum chamber for simultaneously opening the suction port and gasoline intake port valves, and closing the air port valve, or vice versa.

5. The combination with an intake pipe for internal combustion engines having an intake passage extending longitudinally thereof, a suction conduit extending longitudinally through the intake pipe and having communication with the intake passage therethrough, in combination with a vacuum chamber secured directly on top of the intake pipe, a wall of said chamber having a passage communicating with the suction conduit and with the upper end of the vacuum chamber, said vacuum chamber having in its upper end a fuel inlet port, valves for controlling said port and the passage in the wall of the vacuum chamber, and float means disposed in the vacuum chamber and adapted to simultaneously operate the said valves.

6. The combination with an intake pipe or casting having an intake passage extending longitudinally thereof and terminating be-

between the ends of the intake casting and the intake passage in a downwardly projecting inlet end, said intake pipe having a suction conduit extending longitudinally there-
5 through and communicating at one end with the intake passage, said intake pipe having a passage opening through its upper and lower faces, a vacuum chamber secured directly on top of the intake pipe over said last
10 mentioned passage, a wall of the vacuum chamber having a passage communicating with the suction conduit and communicating

with the upper end of the vacuum chamber, means within said chamber for maintaining a constant level of fuel therein, and a carburetor secured to the under side of the intake pipe casting beneath the liquid fuel passage in the intake casting and the main intake passage of the manifold whereby the carburetor will be constantly furnished with
15 20 liquid fuel from the vacuum chamber.

In testimony whereof I affix my signature.

HENRY GREEN.
